United States Patent Office

Des. 213,431
Patented Mar. 4, 1969

213,431

KNOB

Leland George Stone, Mundelein, Ill., assignor to
Amerock Corporation, Rockford, Ill., a corpora-
tion of Connecticut

Filed Mar. 25, 1968, Ser. No. 11,338

Term of patent 14 years

U.S. Cl. D8—144
Int. Cl. D8—03

FIGURE 1 is a front view of a knob incorporating my new design.

FIG. 2 is a side view of a knob as seen from the right in FIG. 1.

FIG. 3 is an enlarged sectional view taken along the line 3—3 in FIG. 1.

FIG. 4 is an enlarged perspective view of the knob.
I claim:

The ornamental design for a knob, as shown.
